UNITED STATES PATENT OFFICE

161,618

MAKE-UP MIRROR

Roy A. Ferguson, Santa Monica, Calif.

Application December 31, 1948, Serial No. 150,482

Term of patent 14 years

(Cl. D86—10)

To all whom it may concern:

Be it known that I, Roy A. Ferguson, a citizen of the United States and residing at Santa Monica, in the county of Los Angeles and State of California, have invented a new, original, and ornamental Design for a Make-Up Mirror, of which the following is a specification, reference being had to the accompanying drawing, forming a part hereof.

Fig. 2 is a side elevational view, with the mirror portion shown at a tilted angle.

I claim:

The ornamental design for a make-up mirror, as shown.

ROY A. FERGUSON.
